The ornamental design for a housing for a material testing machine, as shown and described.

DESCRIPTION

FIG. 1 is a perspective view of a first embodiment of the housing for a material testing machine.

FIG. 2 is a front view of the housing for a material testing machine illustrated in FIG. 1.

FIG. 3 is a rear view of the housing for a material testing machine illustrated in FIG. 1.

FIG. 4 is a left side view of the housing for a material testing machine illustrated in FIG. 1.

FIG. 5 is a right side view of the housing for a material testing machine illustrated in FIG. 1.

FIG. 6 is a top view of the housing for a material testing machine illustrated in FIG. 1.

FIG. 7 is a perspective view of an second embodiment of the housing for a material testing machine.

FIG. 8 is a front view of the housing for a material testing machine illustrated in FIG. 7.

FIG. 9 is a rear view of the housing for a material testing machine illustrated in FIG. 7.

FIG. 10 is a left side view of the housing for a material testing machine illustrated in FIG. 7.

FIG. 11 is a right side view of the housing for a material testing machine illustrated in FIG. 7.

FIG. 12 is a top view of the housing for a material testing machine illustrated in FIG. 7.

FIG. 13 is a perspective view of a third embodiment of the housing for a material testing machine.

FIG. 14 is a front view of the housing for a material testing machine illustrated in FIG. 13.

FIG. 15 is a rear view of the housing for a material testing machine illustrated in FIG. 13.

FIG. 16 is a left side view of the housing for a material testing machine illustrated in FIG. 13.

FIG. 17 is a right side view of the housing for a material testing machine illustrated in FIG. 13; and,

FIG. 18 is a top view of the housing for a material testing machine illustrated in FIG. 13.

The bottom view is not claimed. The dashed or dotted lines form no part of the claimed design.
